UNITED STATES PATENT OFFICE.

WILLIAM P. HENSZEY, OF PHILADELPHIA, PENNSYLVANIA.

DESIGN FOR A FRAME FOR LOCOMOTIVES.

SPECIFICATION forming part of Design No. 24,628, dated August 20, 1895.

Application filed May 3, 1895. Serial No. 548,058. Term of patent 14 years.

To all whom it may concern:

Be it known that I, WILLIAM P. HENSZEY, a citizen of the United States, residing in Philadelphia, Pennsylvania, have invented a certain new and useful Design for a Frame for Locomotives, of which the following is a specification.

My design for the frame of a locomotive is fully illustrated in the accompanying drawing, which represents the frame in perspective.

The essential feature of the design is the peculiar form of the upper portion of the frame, which is depressed, as clearly illustrated.

The upper bar A of the frame is continuous and is depressed at a, as shown, and depending from the portion A' of the frame are pedestals b, and depending from the portion A² of the frame are pedestals b', and extend-

ing from one pedestal b' to the end of the upper bar is an angle-bar b², and extending from the opposite pedestal b' to a pedestal b is a bar b³. A connecting-bar b⁴ extends from one pedestal b to another, and a projection b⁵ extends from the lower portion of the end pedestal b, as clearly illustrated in the drawing.

I claim—

The design for the frame of a locomotive as herein described and shown in the accompanying drawing.

In testimony whereof I have signed my name to this specification in the presence of two subscribing witnesses.

WM. P. HENSZEY.
